(57) CLAIM

The ornamental design for slip-on footwear, as shown and described.

DESCRIPTION

FIG. 1 is a front perspective view of the slip-on footwear according to the design;

FIG. 2 is a rear perspective view thereof;

FIG. 3 is a right perspective view thereof;

FIG. 4 is a left perspective view thereof;

FIG. 5 is a top plan view thereof; and,

FIG. 6 is a bottom plan view thereof.

The broken lines on the shoe upper represent stitching and form a part of the claimed design. The shaded areas of the shoe upper illustrate a contrasting appearance. The broken lines included in FIG. 6, illustrating the sole of the shoe, form no part of the claimed design.
